UNITED STATES PATENT OFFICE

WILLIAM M. BULLARD, OF HOUSTON, TEXAS

SNUFFER

Application filed March 12, 1928. Serial No. 260,853.

This invention relates to new and useful improvements in a snuffer.

One object of the invention is to provide an apparatus of the character described designed to be attached to a pipe or casing in a well bore and through which the fire may be extinguished in case gas is encountered and ignited, in drilling a well.

In drilling oil or gas wells gas under great pressure is sometimes encountered and the gas may become ignited, either from heat generated by the friction of the gas with the well casing, in escaping, or from other causes, and in such event the fire is difficult to extinguish on account of the great heat and great pressure. It is the prime object of this invention to provide an apparatus of the character described which is controllable at a distance from the well and whereby the pipe, or casing, through which the gas is escaping, may be completely closed, and steam forced into said casing, or pipe, to counteract the force of the escaping gas and to smother the flames.

Another object of the invention is to provide an apparatus of the character described which is of very simple construction and positive in operation and which may be controlled at a distance from the well and with safety to the workmen.

With the above and other objects in view this invention has particular relation to certain novel features of construction operation and arrangement of parts an example of which is given in this specification and illustrated in the accompanying drawings, where-in:

Figure 1 shows a side elevation of the device, partly in section, and

Figure 2 shows a horizontal sectional view thereof.

Referring now more particularly to the drawings, wherein like numerals of reference designate similar parts in each of the figures the numeral 1 designates the casing or pipe in a well bore. Incorporated into this casing near its upper end, there is a gate valve 2 provided for the purpose of controlling the flow of fluid through the casing.

Above the valve 2 the casing is enlarged,

forming a snuffer valve casing 3, one side of which is formed with a removable plate 4 which is formed into a housing 5. There is a snuffer valve 6 hinged at 7 to the inner side of the plate 4 and normally hanging in vertical position to one side of the fluid passage way through the casing 1.

There is a steam line 8 whose inner end is connected into the housing 5 and this line may be opened and closed through the valve 9. There is a latch 10 pivotally mounted in the housing 5 and whose inner end is formed into a catch 11 normally engaged in the eye 12 on the outer side of the valve 6 and held in such engagement by the pull spring 13. The outer end of the latch carries a depending disc 14, rigid therewith, and normally closing the inner end of the line 8.

There is a push spring 15 interposed between the lower edge of the valve 6 and the anchor 16 in the housing 5.

In case gas under pressure be encountered and in flowing through the casing 1 becomes ignited it usually produces a very hot fire so that the valve 2 cannot be closed to shut off the flow of gas. In such event the valve 9 may be opened and steam, or other fluid, under pressure, permitted to flow through said line 8. This fluid will operate to force the disc 14 inwardly and thus disengage the catch 11 from the eye 12. Thereupon the spring 15 will force the valve 6 out into the stream of gas flowing through the casing 1 and said valve 6 will be forced upwardly and seated, and held seated, against the seat 17 formed in the upper end of the casing 3 and the flow of gas will thus be stopped and the flame above the valve 6 snuffed out. The steam introduced into the casing 1 beneath the valve 6 will counteract the gas pressure and will also smother out the fire beneath said valve. When the fire is extinguished the gas pressure may be controlled through the outlet line 18, leading out from the casing 3, and controlled by the valve 19.

While I have shown what I now consider the preferred form of the invention it is obvious that modifications may be made therein and equivalents substituted for the parts shown and the right is reserved to 100

make such mechanical changes and substitutions as may be found desirable and such as may be comprehended within the scope of the appended claims.

5. What I claim is:—

1. The combination with a casing in a wellbore, of a snuffer valve, a releasable latch normally holding said valve in position at one side of the passageway through the casing, a fluid pressure line adapted to conduct fluid in said line into the case beneath the valve as well as to direct fluid under pressure against said releasable latch to release the same to permit said valve to swing into position to close said passageway.

10. The combination with a tubular casing in a wellbore through which gas, under pressure may escape from said bore, a fluid pressure line entering the casing, a swingable snuffer valve movable into active position to block said casing and into inactive position to permit the free flow of gas through said casing, a releasable latch normally holding said valve in inactive position, and including a member disposed to be actuated by fluid flowing through said line to effect the release of said latch whereby the valve is permitted to swing into active position.

15. The combination with a tubular casing in a wellbore through which gas, under pressure may escape from said bore, a fluid pressure line entering the casing, a snuffer valve movable into active position to block said casing and into inactive position to permit the free flow of gas through said casing, a releasable latch means normally holding said valve in inactive position, and including a member disposed to be actuated by fluid flowing through said line to effect the release of said latch, and a spring effective to actuate said valve, when so released, into the path of the escaping gas, whereby said valve is moved into said active position.

20. The combination with a pipe in a wellbore through which fluid, under pressure, may escape from said bore, a fluid pressure line entering said pipe, a swingable valve movable into active, or closed, position to close said pipe to prevent the escape of said fluid from the well and movable into inactive, or open, position to permit the escape of said fluid from the well, latch means releasable through the action of the fluid flowing through said line and normally adapted to hold said valve in inactive, or open, position and said valve being so disposed as to be actuated into closed position by the fluid escaping through said pipe, when said means are released.

25. The combination with a pipe in a wellbore through which fluid, under pressure, may escape from said bore, a fluid pressure line entering said pipe, a valve movable into active, or closed position to close said pipe to prevent the escape of said fluid from the

well and movable into inactive, or open, position to permit the escape of said fluid from the well, means releasable through the action of the fluid flowing through said line and adapted to hold said valve in inactive, or open position, said means including a latch in engagement with said valve and a release member carried by the latch and adapted to be actuated by the pressure of the fluid flowing through said line to release the latch from said valve.

30. The combination with a pipe in a wellbore through which fluid under pressure may escape from said bore, a fluid pressure line entering said pipe, a swingable valve movable into active, or closed, position to close said pipe to prevent the escape of said fluid from the well and movable into the inactive, or open, position to permit the escape of said fluid from the well, means releasable through the action of the fluid flowing through said line and adapted to hold said valve in inactive, or open, position, and means for actuating the valve, when released, into the path of said escaping fluid whereby said fluid will swing the valve into active position.

35. The combination with a pipe in a wellbore through which fluid, under pressure, may escape from said well, said pipe having an inside valve seat, of a snuffer valve movable into active position, against said seat, to close said pipe and prevent the escape of said fluid, and movable into inactive, or open, position, an eye carried by said valve latch means adapted to engage in the eye and hold said valve in said open position and means for releasing said holding means from said valve, said releasing means comprising an actuator connected to the holding means and a fluid pressure line entering said pipe and disposed to project pressure fluid against said actuator.

40. The combination with a pipe in a wellbore through which fluid, under pressure, may escape from the bore, of a swingably mounted valve in the pipe adapted to be actuated by the escaping fluid to close said pipe against the further escape of said fluid, means releasable through the influence of pressure fluid, normally holding said closing means in open position and a fluid pressure line entering the pipe beneath said valve through which said pressure fluid may be conducted into the pipe as well as applied to said releasable means to effect the release thereof from said closing means.

45. In testimony whereof I have signed my name to this specification.

50. WILLIAM M. BULLARD.
